COMBINED TABLE, TELEVISION STAND,
LAMP AND ANTENNA

Leon Barrett, The Stafford House, 5555 Wissahicon Ave.,
Philadelphia, Pa.

Filed Oct. 17, 1962, Ser. No. 72,152

Term of patent 14 years

(Cl. D33—14)

FIG. 4.

FIG. 5.

*FIG. 6.FIG. 7.*FIG. 1 is a front elevational view of a combined table, television stand, lamp and antenna embodying my new design;

FIG. 2 is a top plan view;

FIG. 3 is a bottom view;

FIG. 4 is a right side view, portions thereof being broken away for convenience of illustration;

FIG. 5 is a left side view thereof;

FIG. 6 is a rear elevational view of the article of FIG. 1. FIGURE 7 is a front perspective view thereof.

I claim:

The ornamental design for a combined table, television stand, lamp and antenna, as shown and described.
